J. E. GOODMAN ET AL

ELECTRIC HEATING ATTACHMENT FOR CARBURETORS

Filed March 13, 1920

FIG. 1

FIG. 2

INVENTOR

JOHN E. GOODMAN,
JOSEPH M. GARR.

BY
Lockwood & Kirkwood
ATTORNEYS

UNITED STATES PATENT OFFICE.

JOHN E. GODMAN AND JOSEPH M. GARR, OF LAFAYETTE, INDIANA; SAID GARR
ASSIGNOR TO SAID GODMAN.

ELECTRIC HEATING ATTACHMENT FOR CARBURETORS.

Application filed March 13, 1920. Serial No. 365,410.

To all whom it may concern:

Be it known that we, JOHN E. GODMAN and JOSEPH M. GARR, citizens of the United States, and residents of Lafayette, county 5 of Tippecanoe, and State of Indiana, have invented a certain new and useful Electric Heating Attachment for Carburetors; and we do hereby declare that the following is a full, clear, and exact description thereof, 10 reference being had to the accompanying drawings, in which like numerals refer to like parts.

The chief object of this invention is to provide the carburetor or the intake manifold of an internal combustion engine with an improved heating element for assisting the evaporation of the hydrocarbon fuel atomized and carburized by the usual carburetor.

20 The main feature of the invention consists in constructing the improved heating element of suitable materials and operating the same from the battery of the motor vehicle or the like, of which the engine is a 25 part.

Another feature of the invention consists in positioning the electrical heating means adjacent the walls of the fuel intake passageway such that the efficiency of the fuel 30 supply is not impaired.

A further feature of the invention is that the heating means may be supplied to the carburetor flange and inserted therein after recessing the same.

35 The full nature of the invention will be understood from the accompanying drawings and the following description and claims.

In the drawings Fig. 1 is an elevation 40 view of the invention showing the same applied to an internal combustion engine. Fig. 2 is an enlarged plan view of the heating element with a portion broken away to show other parts in detail. Fig. 3 is a central sectional view taken on line 3—3 of Fig. 2.

In Fig. 1 there is shown an internal combustion engine 10 provided with the usual exhaust manifold 11, intake manifold 12, and carburetor 13. The invention in this 50 figure is shown positioned between the ends of the intake manifold and the carburetor and secured thereto by suitable means, such as the bolts 14 and the like.

The improved heating element comprises 55 a body portion 15, substantially elliptical in

form. Said body portion near the extremities of the major axis is provided with a plurality of openings 16 adapted to receive the bolts 14 for securing said heating element to the carburetor or the intake manifold, or both as desired. The body portion 15 is provided with a central circular opening 17 extending therethrough. Communicating with said circular opening and concentric therewith is an annular semi-circular groove 18. Positioned within said groove is a semi-annular shield 19 which serves to direct the heat centrally and away from the body portion 15, as well as electrically insulate the individual coils 20 of the substantially annular, helical, electric heating coil 21. The heating coil 21 is provided with terminal posts 22, said posts being suitably insulated from each other and the body portion 15 by means of the insulating plate 23 and insulating bushings 24, substantially as shown. Suitable nuts 25 secure the circuit wires to the heating element.

The electrical circuit is herein shown comprising the usual storage battery 26, a 80 switch 27, suitably positioned on the cowl, or dash, the ammeter 28, and the ground connection 29. Insulated wires connect the battery, switch, ammeter and heating element in series, as shown, and said heating element will be energized when the switch 27 is operated to close the circuit through the battery.

As shown clearly in Fig. 2, the carburized mixture will pass upwardly through the exposed portions of the annular, helical heating coil and be heated to further vaporize the hydrocarbon fuel. In Fig. 1 the heating element is shown positioned between the adjacent receiving end of the intake manifold and the discharging end of the carburetor. Said heating element, however, may be positioned in the flanges of either the intake manifold or the discharge portion of the carburetor. The heating element also 100 may be positioned upon the intake manifold and upon the discharge portion of the carburetor such that the heating coils 21 will be in contact with either of said parts, as desired, instead of in direct contact with the 105 carburized mixture. When not in direct contact with the carburized mixture, it will, of course, be understood that suitable electrical insulating material must be interposed between the metallic intake or carburetor and 110

the heating coils. The preferred, most economical and easily mounted operating position is that shown in Fig. 1, wherein the heating coils 21 are directly exposed to the passing carburized mixture and the heating element is interposed between the adjacent end of the intake manifold and the discharging end of the carburetor.

While the invention has been described in great detail, it will be understood that the broader features thereof, to-wit, pre-heating the carburized mixture, especially when starting a cold motor by means independent of the usual pre-heating devices heretofore employed, is not to be limited by the detail with which the same has been described, as many modifications thereof will suggest themselves to those skilled in the art. It will be noted that the application of this heating device to the motor is adaptable to installation either between the carburetor and manifold, or between the manifold and engine, being secured adjacent the flanged connections of the carburetor or manifold as the case may be, or may be installed in the carburetor flange or in the side of the engine. It may also be made helical, straight, staggered, or any other shape to conform with the shape of the flanged connection of the members between which it is secured or affixed.

The invention claimed is:

1. An electric heater for the intake of an internal combustion engine, comprising a body portion provided with a central intake

opening therethrough for the passage of fuel to the engine, an annular electrical heating element surrounding said central opening and secured to the inner wall thereof, said element being arranged to extend partially into said opening and leave a central free passage therethrough.

2. An electric heater for the intake of an internal combustion engine, comprising a body portion provided with a central opening therethrough, an annular semi-circular groove in the wall of said body portion communicating with said opening and concentric therewith, and an annular electrical helical heating coil positioned in said groove adjacent and projecting partially into said opening so as to leave the central portion of said opening free for the passage of fuel therethrough.

3. An electric heater for the intake of an internal combustion engine comprising a body portion provided with an intake opening and an inner peripheral groove communicating with said opening, insulating material positioned in said groove, and a helical heating coil mounted in said inner peripheral groove positioned adjacent said insulating material and extending partially into said opening so as to preheat the fuel passing through said opening and leave an unobstructed central passage therethrough.

In witness whereof, we have hereunto affixed our signatures.

JOHN E. GODMAN.
JOSEPH M. GARR.
